UNITED STATES PATENT OFFICE.

JULIUS F. G'SELL, OF JERSEYVILLE, ILLINOIS, ASSIGNOR TO INTERNATIONAL SHOE COMPANY, OF ST. LOUIS, MISSOURI, A CORPORATION OF DELAWARE.

METHOD OF MAKING SPRING-HEEL SHOE SOLES.

Application filed July 16, 1923. Serial No. 651,733.

To all whom it may concern:

Be it known that I, JULIUS F. G'SELL, a citizen of the United States, residing at Jerseyville, Jersey County, State of Illinois, have invented a new and useful Method of Making Spring-Heel Shoe Soles, of which the following is a specification.

This invention relates to a method of making spring heel shoe soles, and consists in the novel method of procedure for practicing the method hereinafter disclosed.

The present practice in the manufacture of spring heel soles consists in forming a flat sole blank separately in a press so as to provide an upwardly deflected line across the sole at the forward portion of the heel section. The heel lift, consisting of a flat section with a beveled edge, is then cemented thereto by applying cement to the face of the heel section of the sole and to the under face of the lift, allowing the cement to partially dry until it reaches the tacky state and then pressing the two parts together by hand. This practice requires considerable labor as difficulty is experienced in properly centering the lift on the heel section. Difficulty is also experienced in this practice in securing the bevel front edge of the heel lift to the face of the inclined line formed in the sole, it usually being necessary to tack the beveled edge in place.

The object of the present invention is to overcome the expensive operations now employed in making spring heel soles, to reduce the expense thereof, and to form a more uniform shoe sole wherein the beveled edge of the heel lift is securely adhered to the inclined line at the forward portion of the heel section.

These purposes, as well as other advantages, are accomplished in the manner hereinafter more fully disclosed by the use of the apparatus illustrated in the accompanying drawings in which—

Fig. 1 is a top plan view of the apparatus.
Fig. 2 is a side elevation thereof.

Fig. 3 is a bottom plan view of the top section of the mold.

Fig. 4 is a top plan view of the bottom section of the mold.

Fig. 5 is a vertical section through the same.

Fig. 6 is a cross section taken on the line 6—6 of Fig. 1.

Fig. 7 is a cross section taken on the line 55 7—7 of Fig. 1.

Fig. 8 is a top plan view of the shoe sole with the heel lift applied thereto.

Fig. 9 is a side elevation of the heel lift.

Fig. 10 is a side elevation of the sole prior 60 to molding of the same.

Fig. 11 is a side elevation of the molded heel section of the sole with the heel lift applied thereto.

As illustrated in the drawings the apparatus for practicing the method comprises a mold including a bottom section 1 preferably made of wood. In the upper face of this bottom section of the mold there are formed two cavities extending inwardly 70 from each end of the mold. The inner portion of each of these cavities is formed with a flat wall 2 for supporting the upper face of the heel lift when the shoe sole is inserted therein in inverted position. The side walls 3 of the inner ends of the cavities conform generally to the curvature of the edges of the heel section of the soles and the heel lifts applied thereto. These side walls have a downwardly extending section 4 in the plane with the plane of the inclined wall forming the line at the forward portion of the heel section of the sole. The front portion of each of the cavities is formed with an arch section 5 to support and form the 85 concave portion of the shoe sole forward of the forward end of the heel lift. At the side edges of the arch section of the cavity are walls 6 that are substantially on a plane with the forward edge of the walls 4 and 90 also substantially on a plane with the top of the arched portion 5 of the cavity.

Intermediate of the inner edges of the cavities formed in the base section is a transverse channel 7 at the center of which is formed a cylindrical opening 8. On the bottom wall of the base section and surrounding the opening of the cavity 8 is a retaining plate 9 held in place by suitable retaining means, such as wood screws 10.

Seated in the cavity formed by the opening 8 is a post comprising a circular base section 11 to which is connected a stud 12 preferably rectangular in cross section. The stud 12 has ratchet teeth formed on one edge 105 and the post is positioned in the cavity formed by the opening 8 in such a manner that the base section thereof seats on the

upper wall of the retaining plate 9, the stud 12 extending vertically above the upper plane of the base of the mold with ratchet teeth facing outwardly toward one side 5 edge of the mold. A retaining plate 13 having an opening 14 therein is secured in position in the channel 7, with the stud 12 projecting through said opening 14. A cotter pin 14^a may be mounted 10 in an opening in the stud above the plate 13 for retaining the post in position when the plate 9 is removed. An expansion spring 15 is mounted in the cavity 8 and bears against the base section 11 15 of the post at one end and against the under face of the retaining plate 13 at the other end, so as to resiliently support the post in position in the cavity. The post constitutes one element of a latch device for 20 holding the two mold sections together.

Dowel pins 16 project upwardly from the base section of the mold for centering the upper section thereof when the same is placed in position.

25 The upper section of the mold has its under face formed to conform in general contour with the bottom of the shoe sole with the heel lift applied thereto, there being provided a flat wall 17 and a flat wall 30 18 fitting over the heel area of the shoe sole and inclined sections 19 and 20 arranged to form the downwardly deflected line forward of the heel section of the sole, and the concave portions 21 and 22 forming the arched 35 portion of the sole. Intermediate of the walls 17 and 18 is a centrally disposed opening 23 into which the upper end of the post extends. There is also formed in the upper 40 section of the mold dowel pin openings 24 that cooperate with the dowel pins 16 in centering the two sections of the mold.

A latch bolt housing 25 is secured to the inner face of the upper mold section adjacent to the opening 23, and a latch bolt 45 26 is mounted in said housing in such a manner that it projects across the opening 23, said latch bolt having its projecting edge formed with ratchet teeth adapted to cooperate with the ratchet teeth of the post 50 to latch the two mold sections together. The latch bolt is provided with a push rod 27, said push rod extending outwardly beyond the edge of the mold section. A spring 28 attached at one end to the push rod and at the opposite end to the wall of 55 the mold section normally tends to move the latch bolt inwardly into engagement with the stud of the post. To release the latch pressure is exerted on the push rod 27, 60 unlocking the latch device.

The method of making the spring heel soles by the use of the apparatus described consists in inserting the heel lifts in reverse position in each end of the bottom mold section, applying over the area thereof a

quantity of glue, it being observed that glue may be employed instead of cement thus effecting a substantial saving in manufacturing cost. If preferred, the glue may be applied to the inner face of the heel lift before the same is inserted in the mold cavity. A flat sole is then placed in each of the cavities of the bottom mold section in such a way that the heel section is centered upon the heel lift. The top mold section is then 70 centered upon the base section of the mold and pressed downwardly, being retained in position by the latch device. A plurality of the molds are arranged in this way and are positioned in a press and pressure applied to the mold. The pressure results in 75 clamping the mold sections tightly together, forming the completed shoe sole and adhering the heel lift uniformly throughout its 80 entire area including a tight connection 85 along the beveled edge of the heel lift with the contiguous area of the heel section of the shoe.

As the mold constitutes a complete template for centering the heel lifts and the soles uniformly in the completed product is obtained. The process may be carried out with a great saving in labor. The line section and the arch section of the sole may be formed uniformly and the contiguous 95 surfaces of the heel lift and heel section of the sole are closely united throughout their entire area, thus obviating curling of the edges of the beveled section of the heel lift and making it unnecessary to nail the beveled section of the heel lift to the line on the shoe sole.

I am aware that the invention may be modified in certain particulars without departure from the spirit and scope thereof. 105 I do not limit myself unessentially, but what I claim and desire to secure by Letters Patent is:—

1. The method of making spring heel soles, which consists in shaping a flat heel 110 blank to provide a heel lift receiving portion, and simultaneously bonding a lift to said lift receiving portion.

2. The method of making spring heel soles, which consists in shaping a flat heel 115 blank to provide an upwardly inclined wall forward of the heel section, and simultaneously bonding a lift to said heel portion and said inclined wall in one operation.

3. The method of making spring heel soles, which consists in placing a heel lift 120 in a mold, adjusting a sole blank in juxtaposition thereto, there being an adhesive element between the matching faces of the sole and lift, and applying pressure uniformly throughout the area of the lift portion and the heel portion of the sole.

4. The method of making spring heel soles, which consists in placing in a mold a 130 spring heel lift in connection with a flat

sole blank, applying glue to the contiguous surfaces of the lift and heel portions of the sole, and placing the mold under pressure to form the sole and to bond the lift to the heel portion thereof.

5. The method of making spring heel soles, which consists in placing in a base section of a mold having a shape forming cavity a heel lift in inverted position, said heel lift having a glue surface on the face thereof, placing a shoe sole blank on said lift, and clamping the parts in position and then applying pressure uniformly to the heel area of the sole effectively to bond the lift to the sole and to shape the sole.

6. The method of making spring heel soles which consists in superimposing the heel portion of a sole blank upon a heel lift, and then simultaneously shaping said heel portion to conform to the heel lift, and 20 bonding the two together.

7. The method of making spring heel soles which consists in applying pressure to a heel lift and the contacting portion of a sole having a bonding substance between 25 them, whereby the sole is shaped to the heel lift and the two are bonded together simultaneously.

JULIUS F. G'SELL.
